ENGINE EXHAUST RAIN CAP

Bertil Stade, Oak Park, and Edward Hoglund, Park Ridge, Ill., assignors to Mercury Metal Products, Inc., Hillside, Ill., a corporation of Illinois

Filed Apr. 4, 1960, Ser. No. 19,604

10 Claims. (Cl. 98—59)

This invention relates generally to protective covering devices for the open ends of upstanding conduits carrying combustive exhaust fumes so as to prevent entry therein of rain, dust, insects and the like during periods when said exhaust fumes are not being discharged. More particularly, the invention is concerned with providing a protective cover assembly of the gravity actuated type which is characterized by a cover member adapted to seat over the open end of said conduit, said cover having secured thereto a counter balanced member which is pivotally supported in such a manner as automatically to raise said cover to an open position during the discharge of said exhaust gaseous products and to return same to a closed position substantially instantaneously with the cessation of flow of said exhaust gases.

Substantial problems have been encountered in the utilization of upstanding exhaust conduits of internal combustion engines employed for operating machinery such as stationary engines, bulldozers, tractors, reapers, combines and the like, said problems involving damage to the engine caused by the entry of rain water, insects and other foreign material through the open end of said exhaust conduit and the accumulation of such material in the interior of said engine. Not only are there harmful mechanical results due to the presence of accumulations of such foreign material within the working parts of the engine, but operative effects typified by failure to ignite, misfiring of the spark-plugs within the system, etc., are also traceable to the presence of such accumulated material. While the engine is operating and the exhaust fumes are being discharged, the updraft of said fumes prevents any foreign material from entering said conduit but, with the cessation of the engine's operation, there is no deterrent to such entry.

Covering devices heretofore used have generally comprised two distinct types. The first type were covers adapted to be secured over the open end of said upstanding exhaust conduit and which remained partially open to allow for escape of exhaust gases and provided a partial baffle against the entry of foreign material therethrough. These covers comprised screens to prevent passage of insects and dirt, but which allowed rain to enter. Some covers of this type were adapted to be clamped in a position spaced from the end of said conduit thus serving as a mere baffle to rain and non-preventive to the entry of insects. In cases of a wind-driven rainfall, the preventive action of such type cover assemblies were practically useless.

A second class of protective cover devices heretofore utilized comprised a cover member to which was attached a pivotally secured balance arm, said arm being pivotally secured to an upstanding bifurcated bracket member, the latter being welded to a clamp member. The clamp is secured on the peripheral surface of the conduit adjacent the open end thereof so that the cover portion is in contact with the upper edge of the clamp body over the open exhaust conduit to close off same. The clamp is tightened in position by means located op-

2

posite the position of the bracket member. The balance arm is pivoted so that the weight of the cover just slightly overbalances said arm so as to remain in a rest position over said conduit. When the engine is started a pocket of exhaust gas forms at the top of the conduit and upsets the balance to raise the cover into an open position. The pressure of the exhausting gases prevents the cover from closing.

Certain disadvantages have been encountered in the last mentioned cover assemblies; namely, the tendency of the cover to remain in open position upon the cessation of the operation of the engine due primarily to the failure of the balance arm to sufficiently force said cover to return against a slight opposite wind pressure; the weakness at the pivot linkage due to the tendency of the arm to move laterally relative the bifurcated portions, the exposure of the inner portions of the pivot means to the elements thereby increasing chances for corrosion damage, and the provision of many exposed upstanding wind-breaking portions with wind resistance characteristics; and lastly, but probably the most important disadvantage, the substantial high cost in manufacture and assembly of such devices.

Accordingly, it is the primary object of the invention to provide a gravity actuated protective cover device for substantially upstanding exhaust conduits which substantially eliminates the disadvantages heretofore encountered; which is economical to manufacture, assemble and install; and which is fool-proof in operation so as to prevent the entry of any foreign material through said exhaust conduit when passage of exhaust gases therethrough ceases.

Another object of the invention is to provide a gravity actuated pivotally supported cover assembly structure offering substantially little resistance to wind pressure and whose operation is not affected thereby.

Still another object of the invention is the provision of such a cover assembly wherein the pivot point is below the level of the conduit's open end and the greatest portion of the weight of the balance arm is distributed below said level whereupon the upraised position of the cover is such as to be little affected by wind pressure and thus is substantially instantaneously returned to a closed position upon cessation of the passage of discharge gases.

An important object of the invention is to provide, in a cover assembly of the character described, a single piece combination clamp and pivot support characterized by locating the tightening means for the clamp and the pivot point on the same side of the clamp thereby reducing the exposure of the individual elements to exterior conditions, as well as reducing the number of juncture points capable of weakening or becoming subject to corrosion damage. The resulting clamp structure is characterized by a substantially even distribution of clamping pressure during operation and is of a construction wherein there is a material cost saving during the manufacturing process.

A still further object of the invention is the provision of such a novel balance arm and pivot combination which sharply reduces the lateral movement of said balance arm and which is capable of instant reaction to the cessation of gaseous flow through said exhaust system; said balance arm being characterized by an integral double wall construction having an extension therefrom to which is secured a cover; and said pivot means being characterized by a staked construction whereby each wall of the balance arm exerts a resilient force against the point of pivot to reduce lateral movement of the cover without interfering in any manner with the rotational movement of said balance arm.

The foregoing and other objects and advantages of the invention will appear as the description thereof evolves, in

connection with which a preferred embodiment of the invention will be described in detail in the specification and illustrated in the accompanying drawing. It is contemplated that minor variations in the structure embodying the invention may occur to the skilled artisan without departing from the scope or sacrificing any of the advantages thereof.

Referring now to the drawing wherein:

Fig. 1 is a perspective view of a tractor wherein the protective cover assembly embodying the invention is shown installed in closed position upon the upstanding exhaust conduit thereof.

Fig. 2 is a fragmentary enlarged elevational view of said exhaust conduit shown in Fig. 1, the broken lines illustrating the cover device in partially open position.

Fig. 3 is a top plan view of the protective cover device shown in Fig. 2.

Fig. 4 is a section taken through line 4—4 of Fig. 2 and in the direction indicated.

The invention basically comprises a protective cover device for the prevention of the entry of rain and the like into the interior of an internal combustion engine such as used in machinery such as tractors and the like, said engines having open ended upstanding exhaust conduits. Although described in connection with such farm equipment, the invention finds substantial application whenever any combustive system requires the presence of an upstanding exhaust conduit the end of which is open. The invention is particularly characterized by the provision of clamp means having integrally secured thereto means for pivotally supporting a balance arm or body member, the latter being attached to a cover plate adapted to fit over the open end of an exhaust conduit to which said clamping means are secured. The balance body-cover combination is so counter balanced by location of its pivot point below the plane of said open conduit that the cover is held biased in contact with the peripheral edge of said conduit to cover same. Pressure of the exhaust gases exerted when the engine is operated is sufficient to overcome the inertia of the balance body and raise the cover from said closed position and hold same in said open position until the flow of gases cease. Stop means are provided to prevent the cover from being forced back past the said pivot point, and sufficient weight is carried by the portion of the balance body below the pivot point immediately and instantly to cause the cover to return to its rest position upon cessation of gaseous exhaust flow. Novel pivot means to be later described are provided to reduce the lateral movement of the cover relative the conduit and to allow for permanent installation thereof.

Fig. 1 illustrates a preferred embodiment of the invention as installed upon the upstanding exhaust pipe 11 of a tractor 10, the said tractor shown in inoperative condition with the covering assembly 20 embodying the invention shown in closed position.

By reference to Fig. 2, the important details of construction of the protective cover device 20 may be ascertained and described. The device 20 comprises a clamp 12, balance arm body 14, and cover 16 secured to one upper end corner of said balance arm body 14 by means of welded flange 18. A portion of said balance arm body extends over said cover 14 at the periphery thereof, likewise a small portion of said balance arm body extends vertically above the horizontal plane of said cover.

The clamp 12 comprises a metal band portion 22 adapted to substantially encircle the outer peripheral surface of the exhaust conduit 11, said band 22 having a pair of lateral extensions 24, each having an aperture therein to accommodate a tightening bolt 23 therethrough, said bolt to be engaged in a nut 26. In the embodiment herein described a flat headed carriage bolt is used and one aperture is square and the other is round. Any other type of tightening screw means may be as equally applicable to bridge the distance between the two ex-

tensions 24. A pair of ears 28 is provided spaced outwardly offset from the extensions 24, and at parallel horizontal planes relative thereto. Each ear 28 is connected to an extension 24 by a bent portion 32. Each ear 28 is provided with an aperture seating therebetween the pivot means generally shown at 34.

The balance arm body 14 comprises a pair of spaced juxtaposed polygonal plates 36 of like configuration, each of said plates 36 having generally the configuration of an irregular rectangle, the horizontal edges thereof being substantially parallel in contrast to the non-parallel vertical edges. The said member 14 is formed preferably from a single blank of steel or the like reverse bent on the fold 38. A pair of circular openings are punched in said plates, each opening opposite the other. A lateral extension of the fold 38 protrudes in overlapping relation to a portion of said cover 16 spaced inward from its edge. The cover overlapping portion of fold 38 is provided with an integral outwardly extending flange member 18, said flange 18 being in surface to surface contact with the top surface of said cover 16 and is permanently secured thereto by means such as welding or the like as indicated at 41.

The pivot means 34 is utilized to pivotally support the balance arm body 14 between the ears 28 so that the cover 16 will be biased in contact with the top edge of the exhaust conduit 11 when the clamp 12 has been secured upon said conduit near the upper portion thereof but spaced from the open end to allow the overlapping cover 16 to be in contact with the top circumferential edges of said open end. Referring to Fig. 4, the pivot means 34 comprise a rivet 42 adapted to pass through the apertures 44 in ears 28, said rivet 42 having a pair of rounded head portions 46 engaging the outer surface of said ears 28 to join said ears in spaced apart relation. Cylindrical bearing member 48 bridges the gap between the pair of ears 28 and is of a length to maintain the gap distance between said ears 28. A bushing 52 is journaled for rotation on the bearing member 48. The length of the member 52 is slightly less than the gap distance between the ears 28 to enable free rotation thereof on said inner bearing member 48 and its inner bore is of suitable diameter to permit this. The bushing member 52 has enlarged portion 54 at one end thereof and a reduced diameter portion 56 at the other.

The openings which are punched in each of the plates 36 of member 14 are of suitable diameter to pass portion 55 of bushing 52 with the enlarged portion 54 abutting the outer surface of one of said plates 36. The bushing 52 is mounted by passing same through said openings in plates 36 as described and the other plate is secured in place thereby securing the member 14 in position by staking the said plate to reduced section 56 of bushing 52 as indicated at 58. This type of connection formed by forcibly inserting bushing 52 through the openings in the plates 36 and forming a thickened portion 58 in said bushing 52 adjacent one of the openings will be referred to as a staked connection and is to be so interpreted throughout the application. The inner bearing 48 is telescopically fitted into the interior of bushing 52, all openings are aligned, the said assembly is placed between the pair of ears 28; all openings are aligned and the rivet 42 slipped through said aligned openings and permanently secured therein.

The location of the pivot point 34 must be so chosen as to be in the upper quadrant of said balance arm body 14 spaced from the edges adjacent the conduit 11. The greatest portion of the balance arm body 14 is found below the point of pivot 34.

It is also apparent that the clamp 12, extensions 24, bent portion 32 and ears 28 may be formed in a single operation. It is also apparent from the above description that the tendency of the plates 36 because of the folded construction to move relative one the other causes

a force to be exerted against the inner walls of the ears 28 thus maintaining the lateral stability of said cover.

From the description of the above structure, the method of operation of the device is believed to be evident. Nevertheless, a brief explanation thereof is included at this time. After the protective cover device 20 has been assembled, the device is ready for use. Band 22 is slipped over the periphery of the exhaust conduit 11, bolt 23 being tightened, by manipulation of nut 26 by any known means, at a point along the length of said conduit closely adjacent the open end thereof, but spaced therefrom so that the cover 16 is in contact with the top edges of said conduit at said open end. Now the device 20 is in covering position preventing the entry of any foreign material into said conduit.

When the engine is turned on, gaseous exhaust fumes are developed which travel through said conduit 11 and are to be discharged at the open end thereof. The gas pressure thus created at the mouth of said conduit forces the cover 16 to raise upwards as indicated by the arrows. The raising of the cover causes the balance arm body 14 to pivot along the axis shown at 34 forcing the lower left hand portion thereof (in Fig. 2) to move downward and toward the conduit, the right hand corner moving toward the conduit's peripheral surface until it is stopped by the bolt 23 acting as stop means. The open position of the balance arm body is thus unnatural, the same being biased to maintain the cover in closed position. Therefore, upon cessation of the gas pressure from the engine, the balance arm immediately returns to its normal position, forcing the cover quickly to assume the former closed position.

An additional feature may be added to the device in order to reduce wear upon the bolt 23 and edges of plates 34 as it acts as a stop member. This feature comprises a small bar of metal welded or integrally formed in position between the plates 36 at 72 which is shown in dotted outline.

The use of said peripheral band structure 22 for the clamp 12, with the tightening means therefor and the pivot supporting structure being located on the same side thereof provide for a uniform distribution of clamping pressure over the entire surface of the clamp without any sharp points of stress as found in prior devices.

Attention is also called to the effective economy of manufacture of the invention due to the substantial reduction in the number of connections necessary to assemble said cover-clamp assembly and install same in operative position.

It is believed that the invention has been sufficiently explained to enable those skilled in the art to understand the same and construct the structures taught thereby, and it is again desired to reiterate that the structure of the invention is capable of wide variation without departing from the scope thereof as defined in the appended claims.

What is claimed to be secured by Letters Patent of the United States is:

1. A cover assembly adapted to be secured upon upstanding exhaust conduits in fuel combustion systems to prevent entry of extraneous material therethrough during the inoperative stages of said systems and comprising: clamp means for securing said assembly to said conduit adjacent the upper end thereof, a cover member seated over the open end of said conduit, a balance arm extending laterally and downward relative to and connected to said cover member, means integral with said clamp means for pivotally supporting said balance arm whereby said cover is biased in seated position, pivot means supported by said last mentioned means to permit rotation of said balance arm around the minor transverse axis thereof, said axis of rotation located to permit the cover to be raised under the influence of exhaust gases passing through said conduit and to immediately return said cover upon cessation of flow of said gases, and said balance arm comprises a polygonal plate member bent back upon it-

self to form a pair of irregular rectangular wall members connected by an integral fold portion and said clamp means being disposed between the pivot means and the conduit.

- 5 2. A structure as claimed in claim 1 wherein said clamp means comprise an open end band portion adapted to substantially encircle the peripheral surface of said conduit adjacent the top thereof, a pair of lateral extensions integral with said band ends, each said extension having an aperture therein to accommodate means for tightening said band, a pair of offset ear members integrally secured to and extending from said extensions parallel thereto, and said ear members comprising said pivot support means.
- 10 15. 3. A structure as claimed in claim 1 in which said pivot means comprise a pair of cylindrical bushing members telescopically engaged one within the other, said inner bushing being of uniform diameter, said outer bushing having an enlarged diameter portion at one end thereof and a narrow diameter portion at the other end, and said balance arm being provided with a passageway accommodating said pair of bushings, said pivot means being secured to said balance arm by means of a staked connection with said narrow diameter portion of said outer bushing.
- 20 25. 4. A gravity actuated protective cover device adapted to be secured upon the upstanding exhaust conduit of an internal combustion engine to prevent the entry of extraneous matter therein during the inoperative stage of said engine, said protective cover device comprising a clamp member having a band portion and a bracket portion integral therewith, the band portion adapted to substantially encircle the peripheral surface of said conduit, the bracket portion carrying means thereon for tightening said band portion, pivot support means carried by said bracket at a point spaced outward from said tightening means, an elongate balance member supported upon said pivot means in a vertical plane relative said clamp, a dish shaped cover member secured to the upper portion of said balance member and seated over the mouth of said conduit in over-hanging relation thereto, the point of pivot of said balance member being chosen below the level of the mouth of said conduit and the major portion of said balance member extending below said point of pivot whereby the cover is biased against the mouth of said conduit, and balanced to open by the pressure of the discharge gases during the engine's operation and to immediately return to its original position over said mouth upon the cessation of discharge flow.
- 30 35. 5. An automatic self closing protective cover assembly adapted to operate in consort with the upstanding exhaust conduit of a fuel combustive system to prevent the entry therein of extraneous material such as rain, insects and the like while said fuel combustive system is inoperative, said assembly comprising a cover member seated over the discharge end of said conduit closing off same, means for securing said assembly upon the exhaust conduit adjacent its discharge end, a double walled counterbalanced member having major and minor transverse axes 40 and secured at one end thereof to said cover member, said member pivotally mounted for limited rotation around its minor transverse axis, and said member being mounted at a point spaced outwardly from and below the horizontal level of the discharge end of said conduit, and means secured to said clamp means on the same side thereof and laterally spaced therefrom for supporting said counter-balanced member, the weight of said counter-balanced member being so distributed as to bias said cover in a seated position and to permit said cover to be raised and held in raised position by the pressure of exhaust gases as same are discharged from the conduit, the cessation of the flow of said gases immediately resulting in the resumption of the cover's normal closed position.
- 45 50. 6. An automatic self closing protective cover assem-
- 55 60 65 70 75

bly as claimed in claim 5 wherein said clamp member comprises a metal band having its ends spaced one from the other, each end having an outwardly facing extension, said extension having matched apertures accommodating tightening means for said clamp, and ear portions integrally secured to said extension and said balance arm being pivotally supported for vertical movement between said second ear portions.

7. A structure as claimed in claim 6 in which said means for tightening said band comprise a threaded bolt adapted to be passed through preformed openings in said first pair of ears and secured therein by a nut, said tightening means also serving as stop means for said balance arm preventing same from rotating past a position wherein in a transverse plane drawn through the longest diagonal portion of said balance arm is parallel to the vertical plane of said conduit.

8. A structure as claimed in claim 5 wherein said balance arm comprises a double walled resilient plate member of irregular rectangular configuration, said member having top and bottom edges parallel one to the other, said top portion closed off by an integral arcuate fold portion, said fold portion having an extension secured to the said cover, and each plate member is provided with an equal diameter opening, one opposite the other and located in the upper quadrant portion thereof, and said pivot means is passed therethrough and staked therein.

9. A structure as claimed in claim 5 wherein said pivot means comprises a rivet member, and a pair of telescopically engaged bearing members rotatably supported thereon, the inner member being of hollow cylindrical construction and the outer bearing member having an enlarged portion adjacent one end thereof and a decreased diameter portion adjacent the other, said pair of bearing members adapted to be inserted in preformed openings in the balance member body with one portion thereof being staked in place at said narrow diameter portion.

10. An automatic protective cover assembly adapted to operate in consort with the upstanding exhaust conduit of a fuel combustion system for preventing the entry therein of extraneous material such as rain, insects and the like, said cover assembly comprising: a cover member seated over the discharge end of said conduit, said cover having a down-turned saucer-like configuration and having its circumferential edge comprising a flange overhanging said discharge end, a clamp member for securing said assembly upon the upper portion of said exhaust conduit closely adjacent said discharge end, said clamp member comprising a band portion having its ends spaced one from the other and adapted to substantially fit around the peripheral surface of said conduit, a pair of outwardly extending bracket portions each integral with one end of said band portion, said bracket portions extending in planes parallel one to the other, said bracket portions carrying means thereon for tightening said band portion in position, and said bracket portions having integral and parallel extensions therefrom adapted to carry pivot means therein, an irregularly shaped balance arm secured at one end to said cover and mounted for pivotal rotation between said extensions, pivot means supporting said balance arm, the location of 25 the pivot point being chosen whereby the cover is biased in said seated position, the balance arm being so counter balanced to bias said cover in seated position and permit same to be actuated to an open position under the influence of the exhaust gases being discharged and to immediately return said cover to its seated position upon cessation of flow of said exhaust gases.
